UNITED STATES PATENT OFFICE.

HENRY S. BREWINGTON, OF BALTIMORE, MARYLAND.

BOTTLE-CLOSURE.

No. 872,403.

Specification of Letters Patent.

Patented Dec. 3, 1907.

Application filed January 31, 1907. Serial No. 354,959.

To all whom it may concern:

Be it known that I, HENRY S. BREWINGTON, a citizen of the United States, residing at Baltimore city and State of Maryland, 5 have invented certain new and useful Improvements in Bottle-Closures, of which the following is a specification.

My invention relates to bottle closures, the primary object being to provide a simple 10 inexpensive closure especially adapted for bottles containing beer and other beverages.

A further object of the invention is to provide a seal or closure of metal, constructed to contain a suitable packing which extends 15 well over the outer edge of the mouth of a bottle to protect the edge and at same time to form a better sealing contact.

A still further object is to provide the depending cylindrical portion of the cap with a 20 concavo convex flange section to retain the cork and to form a closing means whereby it may be attached to the bottle by pressure 25 upon the outward portion of the concavo convex flange section, and thus cause the flange to continue to close against and under the bead of a bottle head; by this means or 30 method of attaching my improved cap a cushion is formed by the lower edge coming in contact with the glass and the breakage of bottles is thereby greatly reduced. The more outside pressure which is brought to 35 bear on the convex flange the more the holding power and greater sealing contact.

With these several ends in view my invention 35 consists in the improved construction of bottle caps hereinafter described in connection with the accompanying drawings and particularly pointed out in the appended claims.

40 Referring to the accompanying drawings in which like letters and figures indicate corresponding parts in the several views Figure 1 is a vertical section of a bottle head and stopper embodying my invention, showing the cap ready to be forced down on top of the bottle, preparatory to attaching thereto. Fig. 2 is a similar view showing the cap attached, with the flange rolled beneath the bead on the bottle head. Fig. 3 is a perspective view of the cap secured on the bottle head. Fig. 4 is a sectional view showing the cap, with a compressible ring packing within the concavo portion of the depending flange. Fig. 5 is a similar view showing the 45 cap attached to the bottle mouth with the ring compressed. Fig. 6 is a sectional view

of the cap with ring packing in the concave portion of the depending flange. Fig. 7 is a similar view of the metallic cap, without the lining. Fig. 8 is a similar view with cork 60 disk packing or lining. Fig. 9 is a view of the lining or disk. Fig. 10 is a view of the modified packing. Figs. 11 and 12 are edge views of the respective packings of Figs. 9 and 10. 65

In Fig. 1, A represents a bottle head cut away to show the means employed in performing the sealing function; 1, is a bead formed on the mouth of the bottle head A, 2 is a groove formed beneath the bead, 3 is a 70 metallic cap, provided with a concavo convex flange 4, and 5 is a flexible packing disk, made of any suitable material but preferably of cork. In Fig. 2 the flange is shown forced into locking contact in the groove 75 under the bead 1, with the packing 5 compressed between the flange 4 and the bead 1, on the bottle head A, thereby forming the sealing contact.

In Figs. 4, 5 and 6, I have substituted a 80 modified form of packing 6 consisting of a flexible ring, made of suitable size and material, but preferably rubber for the disk, which performs the same function and in the same manner as that of the disk, viz: that it 85 is adapted to be compressed between the flange 4 of the cap and the bead 1 on the bottle head.

It will thus be seen I have invented a closure or cap where a disk may be used or a 90 ring of suitable size and material as a packing, performing the same object of sealing and where the results are obtained by the same means.

When the bottle is to be sealed with my improved cap or closure, a pressure is brought down on top of the cap to force it in sealing relation with the bottle mouth; pressure is then brought against the convex portion of the concavo convex depending flange of the cap, which causes the flange to roll inwardly towards the bottle head until the lower edge of the flange is forced against the bottle neck in the groove under the bead, thus securing a holding or 95 attaching means. This method will secure any limit to the holding power, as more pressure if brought to bear on the convex portion of the flange will cause the flange to embrace the bottle neck all the more and 100 thus form additional holding power. By this means the variation in the sizes of bot- 105

tle heads is provided for and having a rolled flange the risk in breaking the bottle when removing the cap is greatly reduced.

Slight changes might be resorted to in the form and arrangement of the several parts described, without departing from the spirit and scope of my invention, hence I do not wish to limit myself to the exact construction as herein set forth.

10 Having described my invention what I claim as new and desire to secure by Letters Patent, is:

1. A bottle closure made of suitable material provided with a concavo-convex depending flange adapted to be compressed on the bead of a bottle head, the diameter of the depending flange being greater than that of the bead on the bottle head, substantially as described.

20 2. A bottle closure made of suitable material provided with a concavo-convex depending flange, a suitable packing within the closure, the diameter of the flange being greater than that of the bead on the bottle head, substantially as described.

30 3. A bottle closure of suitable material provided with a concavo-convex depending flange, a suitable packing within the closure, the flange and packing being of greater diameter than that of the bead on the bottle head, the flange adapted when compressed

on the convex portion to roll inwardly and secure the packing between the bead on the bottle head and the said flange, substantially as described.

4. The combination with a bottle head formed with an external annular bead, of a cap comprising a disk of sheet metal and having a depending concavo-convex flange, the diameter of the flange of the cap being greater than that of the bead on the bottle head, the cap adapted to be secured to the bead on the bottle head by pressure being applied to the convex portion of the depending flange, substantially as described.

5. The combination with a bottle head formed with an external annular bead, of a cap comprising a disk of sheet metal and having a concavo-convex depending flange, the diameter of the flange being greater than that of the bead on the bottle head, a suitable packing within the cap, adapted to be secured to the bead on the bottle head by pressure applied upon the convex portion of the depending flange of the cap, substantially as described.

In testimony whereof I affix my signature in presence of two witnesses.

HENRY S. BREWINGTON.
